UNITED STATES PATENT OFFICE.

WILLIAM A. KIRKPATRICK, OF ABBYVILLE, KANSAS.

DISPENSING-CONTAINER.

No. 910,826.

Specification of Letters Patent.

Patented Jan. 26, 1909.

Application filed March 27, 1908. Serial No. 423,561.

To all whom it may concern:

Be it known that I, WILLIAM A. KIRKPATRICK, a citizen of the United States, and a resident of Abbyville, in the county of Reno 5 and State of Kansas, have invented a new and Improved Dispensing-Container, of which the following is a full, clear, and exact description.

This invention relates to dispensing containers, more particularly such as are used to hold straws to be served with drinks at bars, soda-water fountains, and the like, and which delivers one straw at a time from a closed receptacle.

15 An object of this invention is to provide a simple and serviceable container having means for holding the straws in a closed receptacle, thus obviating dust and dirt coming in contact with the straws.

20 A further object of the invention is to provide means for releasing one straw at a time from the container, and further means for catching the straw thus released and holding it so that it may easily be taken by the user.

25 The invention consists in the construction and combination of parts to be more fully described hereinafter and particularly set forth in the claim.

Reference is to be had to the accompanying drawings, forming a part of this specification, in which similar characters of reference indicate corresponding parts in all the figures, and in which:

30 Figure 1 is a perspective view of the device; Fig. 2 is an enlarged end view having a part removed to show the means for operating the device; Fig. 3 is an enlarged front view, showing straws in dotted outline; Fig. 4 is a cross section showing the rotatable deliverer means receiving a straw at the inside of the container; and Fig. 5 is a cross section showing the delivering means after a straw has been dispensed.

35 Before proceeding with a more detailed description of my invention, it should be understood that I provide a straw holder, which is constructed to contain any desired number of straws and keep them out of contact with dirt or dust until they are ready to be used. 40 A manually-operable mechanism releases one straw at a time and permits it to drop on a rack suitably positioned to receive the same and which keeps the straw from falling on the counter or on the floor. While this de-

vice has been shown for dispensing straws, it 55 may also be used for dispensing toothpicks, cigarettes, or other articles.

Referring more particularly to the drawings, 1 represents a container or receptacle having end members 2, the latter being extended to form supports 3. Between the end members 2 is carried the back of a receptacle, comprising a wall 4 and an angularly-disposed lid 5 secured thereto by means of hinges 6. The front of the receptacle consists of angularly-disposed walls 4^a, of preferably transparent material, such as glass. A cross support 7 is secured upon the end members 2 by means of screws 8, nails, or the like.

70 Mounted upon the support is a catch 9 of any common preferred form, for instance, such as is shown in the accompanying drawings, for securing the lid 5 by means of a stud 5^a upon the latter. Rotatably arranged in 75 openings 10 in the end members 2, and located partly between the lower wall 4^a and the wall 4 of the container, is a deliverer 11, having a suitable groove 12 for receiving a straw, as shown most clearly in Fig. 4. Suitable studs 13, preferably rounded in form, are mounted on the deliverer 11. Slots 14 in the wall 4 of the container permit the movement of the studs, the latter acting to position a new straw to be taken by the 80 groove 12, as illustrated in Fig. 5, and further agitate the mass of straws to prevent the same from sticking or becoming jammed.

85 Actuating mechanism, consisting of a manually-operable lever 15 located in an opening 19 in one end of the deliverer having a grip 16 at the end thereof, an elongated resilient member 17 having one end secured to the end member 2 and having the other end engaging the lever 15 to resist the movement thereof, and studs 18 to limit the movement of the lever in operating the deliverer, is arranged 90 at the outside of one of the end members 2. A suitable housing 20 is employed to protect the actuating mechanism.

100 Arranged between the supports 3 of the container are cross rods 21. Racks 22 of any suitable material, such as wire or the like, are located under the deliverer for receiving the straws as they fall from the deliverer, being 105 mounted on the end members 2. Metal plates 23, having their lower ends slightly bent, are arranged within the housing for as-

sisting in the positioning of the straws in the deliverer, and are secured to the end members by means of screws or nails 24.

In the operation of the device, straws are received by the groove 12, which is positioned for this purpose adjacent to one of the inclined walls of the container in the normal position of the deliverer. The actuating mechanism then rotates the deliverer, so that 10 the straws are taken from the inside of the container and allowed to drop upon the racks 22. In the meantime, the studs 13 have positioned other of the straws against the inclined wall of the container which is adjacent 15 to the groove, so that when the deliverer is again rotated to its normal position by the action of the resilient member 17, another straw is ready to fall into the groove.

Having thus described my invention, I 20 claim as new and desire to secure by Letters Patent:

A dispensing container comprising a receptacle having end walls extended to form feet,

a back comprising a bottom and an angularly disposed lid, and a front comprising a 25 bottom and an angularly disposed top, the bottom of the front and the bottom of the back being spaced apart from each other to form an opening, the opening extending the full length of the receptacle, a roller journaled in the opening and provided with a longitudinal groove, said roller having behind the groove, projecting studs for the purpose set forth, and being provided outside of the casing with means for rotating the said 30 roller, and curved racks for receiving the material delivered by the groove arranged below the receptacle.

In testimony whereof I have signed my name to this specification in the presence of 40 two subscribing witnesses.

WILLIAM A. KIRKPATRICK.
